(57) CLAIM

The ornamental design for an accessory bag, as shown and described.

DESCRIPTION

FIG. 1 is a front perspective view of the accessory bag;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines showing an accessory bag are included for the purpose of illustrating environment and form no part of the claimed design.

1 Claim, 6 Drawing Sheets
